UNITED STATES PATENT OFFICE.

HUGH H. BELL, OF BURR OAK, KANSAS.

CARBURETER.

1,147,672.

Specification of Letters Patent. Patented July 20, 1915.

Application filed March 31, 1914. Serial No. 828,608.

To all whom it may concern:

Be it known that I, HUGH H. BELL, a citizen of the United States, residing at Burr Oak, in the county of Jewell and State of 5 Kansas, have invented certain new and useful Improvements in Carbureters, of which the following is a specification.

My invention relates to carbureters adapted for use with internal combustion engines 10 and has for its object the provision of a novel form of device wherein a regulable amount of a fixed ratio of air and vaporized fuel are thoroughly intermixed and supplied to the manifold of an engine, the supply 15 of air being augmented by an auxiliary air inlet in addition to the main inlet, the supply of air through the auxiliary inlet and the supply of air and vapor through the main inlet being quickly and easily adjustable to meet different requirements of the 20 same or different engines.

Other objects and advantages such as efficiency, durability, simplicity and the general improvement of the art will be brought 25 out in the following specification and illustrated in the accompanying drawings in which:

Figure 1 is a vertical longitudinal section through the entire device, Fig. 2 is a cross 30 section through the fuel chamber, and Fig. 3 is a detail view.

Referring more particularly to the drawings, the numeral 1 designates the fuel chamber to which the liquid fuel such as 35 gasoline is supplied through a pipe 2. At its upper end, the walls of the chamber 1 are contracted and terminate in a neck 3 into which is screwed a nozzle 4.

Surrounding the chamber 1 and spaced 40 therefrom by arms 5 is an annular shell 6 which has its upper open end screw-threaded, as shown. Extending downwardly from the bottom of the chamber 1 is a bolt 7 which passes through a shell 8 the 45 upper edge of which abuts against the lower edge of the shell 6. The shell 8 is held in the proper relation to the shell 6 by a nut 9 which clamps the shell 8 upon the bolt 7. An air inlet pipe 10 communicates with the 50 shell 8.

Into the upper screw-threaded end of the shell 6 is threaded a tube 11 which is provided intermediate its ends with a plurality of openings 12 which are in the same plane.

Between its lower end and the openings 12 55 the tube 11 is provided upon its internal periphery with vanes 13. A deflecting flange 14 is formed upon the exterior of the tube 11 above and extending downwardly over the openings 12 for a purpose to be described. At its upper end the tube 11 is internally screw-threaded for the reception of a knurled screw 15 which is provided with a screw-threaded opening for the reception of a second knurled screw 16 which 60 is provided with a central passage 17. Lock nuts 18 and 19 are provided upon the screws 15 and 16 respectively for clamping them in desired positions.

A rod 20 is disposed within the tube 11 70 having its upper end passing through the passage 17 and having its lower end provided with a tapered plunger point 21 extending into the nozzle 4. At a point opposite the openings 12 in the tube 11 the 75 rod 20 is provided with a disk 22 fitting the inner periphery of the tube 11. When the disk 22 is even with the openings 12 the plunger point 21 closes the nozzle 4. The rod 17 is normally held in its lowest position 80 by heavy and light coil springs 23 and 24 which abut against the top of the disk 22 and the lower ends of the screws 15 and 16, respectively.

A shell 25 surrounds the upper portion of 85 the tube 11 and forms a mixing chamber. The shell 25 is provided with flanges 26 whereby it may be bolted to the manifold of an engine. The shell 25 is also provided with an opening 27 in its lower wall which 90 communicates with a pipe 28 and is further provided with a sleeve 29 formed upon the lower side of its top wall.

The auxiliary air inlet and its adjusting devices are disposed within the sleeve 29 95 which is in alinement with the opening 27. This auxiliary valve comprises a disk 30 disposed over the opening 27 and provided with an upwardly extending stem 31. A screw 32 is threaded into the sleeve 29 and 100 is provided with a screw-threaded opening for the reception of a second screw 33 which is in turn provided with a central passage 34 which receives and forms a guide for the stem 31. Lock nuts 35 and 36 are disposed 105 upon the screws 32 and 33 respectively for clamping them in desired positions. The disk 30 is normally pressed downwardly by

heavy and light coil springs 37 and 38 which abut against the disk 30 and the screws 32 and 33, respectively.

The operation of the device is as follows: 5 As the pistons in the engine cylinders move, the disk 22 will rise, elevating the plunger point 21 and allow the liquid fuel or gasoline to pass through the nozzle 4 into the tube 11. At the same time air will pass 10 through the pipe 10 around the fuel chamber 1 and thence into the tube 11 where it will mix with the liquid fuel or gasoline, and the mixture so formed will then pass upwardly through the tube 11 and out through 15 the openings 12 after which it will be still more thoroughly mixed by the baffling action of the deflecting flange 14, and as it circulates in the mixing chamber within the shell 25 it will be still further mixed or 20 termingled and then pass by the controlling throttle 39 and into the manifold of the engine.

By adjusting the screws 15 and 16 the 25 springs 23 and 24 can be tensioned to adapt the device for low or high speed. If the speed of the engine is accelerated and a greater supply of air is needed, the increased suction will lift the auxiliary valve disk 30, allowing more air to enter. The springs 37 30 and 38 and the adjusting nuts 32 and 33 permit of the proper adjustment of the tension upon the disk 30.

It will be understood that it is preferable 35 that the pipes 10 and 28 communicate with a drum surrounding the exhaust pipe of the engine or other heating means in order that the air supplied to the carbureter be very hot. By using air heated to a high temperature the fuel in the chamber 1 will be kept 40 hot and will therefore vaporize rapidly. This makes the use of heavier and less active fuels than gasoline a simple and assured matter. Another advantage of this device is 45 that the back pressure and spring tension on the disk 22 is such that the objectionable "fluttering" of the needle valve is eliminated.

Having thus described my invention what I claim is:

50 1. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent said openings, said second named shell being 55 adapted to communicate with the manifold of an engine, a nozzle on said fuel chamber discharging into said tubular member, a rod disposed within said tubular member and having its lower end adapted to close said 60 nozzle, a piston on said rod in alinement 65 with said openings, and adjustable spring tension pressing downwardly on said piston.

2. A carbureter comprising a fuel chamber, a shell surrounding said fuel chamber and provided with an air inlet, a tubular member 70 connected with said shell, a second shell surrounding said tubular member adjacent its upper end, said tubular member being provided with openings communicating with said second named shell, a deflecting flange on said tubular member adjacent said openings, said second named shell being 75 adapted to communicate with the manifold of an engine, a nozzle on said fuel chamber discharging into said tubular member, a rod disposed within said tubular member and having its lower end adapted to close said nozzle, a piston on said rod in alinement with said openings, and adjustable spring tension 80 pressing downwardly on said piston, said tension comprising relatively light and heavy springs disposed one within the other and abutting against said piston and against 85 adjusting screws extending into said second shell.

3. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 90 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, a screw extending into 95 said second named shell, a second screw extending through an opening in said first named screw and provided with a central opening for the reception of said rod, and heavy and light coil springs abutting against 100 said piston and against said first and second named screws, respectively.

4. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 115 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement 120 with said openings, and adjustable spring tension pressing downwardly on said piston.

5. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 125 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement 130 with said openings, and adjustable spring tension pressing downwardly on said piston.

with said openings, and adjustable spring tension pressing downwardly on said piston, and an auxiliary air inlet comprising a disk adapted to seat over an opening in said second named shell, and adjustable spring tension on said disk.

5. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent said openings, said second named shell being adapted to communicate with the manifold of an engine, a nozzle on said fuel chamber discharging into said tubular member, and 50 means for normally closing said nozzle.

10. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 55 said openings, said second named shell being adapted to communicate with the manifold of an engine, a nozzle on said fuel chamber discharging into said tubular member, and a rod disposed within said tubular member and having its lower end adapted to close said nozzle, a piston on said rod in alinement with said openings, a screw extending into said second named shell, a second screw extending through an opening in said first named screw and provided with a central opening for the reception of said rod, and heavy and light coil springs abutting against 60 said piston and against said first and second named screws, respectively, said second named shell being provided with an air inlet opening, a disk valve seated over said opening, a screw extending into said second named shell, a second screw extending through said screw, and relatively heavy 65 and light coil springs abutting against said disk and said last named screws.

15. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 70 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

20. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 75 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

25. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 80 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

30. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 85 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

35. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 90 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

6. A carbureter comprising a fuel chamber,

ber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 40 said openings, said second named shell being adapted to communicate with the manifold of an engine, a nozzle on said fuel chamber discharging into said tubular member, and 45 means for normally closing said nozzle.

7. A carbureter comprising a fuel chamber, a shell surrounding said fuel chamber and provided with an air inlet, a tubular member connected with said shell, a second shell surrounding said tubular member adjacent its upper end, said tubular member being provided with openings communicating with said second named shell, a deflecting flange on said tubular member adjacent 50 said openings, said second named shell being adapted to communicate with the manifold of an engine, a nozzle on said fuel chamber discharging into said tubular member, a rod disposed within said tubular member and having its lower end adapted to close said nozzle, a piston on said rod in alinement with said openings, and means for producing a downward pressure on said piston to prevent fluttering.

In testimony whereof I hereto affix my signature in the presence of two witnesses.
